CLAIM

The ornamental design for a strapping, as shown and described.

DESCRIPTION

FIG. 1 is a front perspective view of a strapping showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the strapping where the strapping is in a first configuration of use;

FIG. 10 is a perspective view of the strapping where the strapping is in a second configuration of use;

FIG. 11 is an enlarged view taken from portion 11 shown in FIG. 1;

FIG. 12 is an enlarged view taken from portion 12 shown in FIG. 2; and,

FIG. 13 is an enlarged right side elevational view of the strapping.
